ISAAC W. VALANCE, OF TROY, NEW YORK.

Letters Patent No. 88,594, dated April 6, 1869.

IMPROVED QUILTING-FRAME.

The Schedule referred to in these Letters Patent and making part of the same.

To all whom it may concern:

Be it known that I, ISAAC W. VALANCE, of the city of Troy, in the county of Rensselaer, and State of New York, have invented a certain new and useful Improvement in Quilting-Frames, or Couplings therefor, of which the following is a full and exact description, reference being had to the accompanying drawing, in which—

Figure 1 is a plan, and

Figure 2, an elevation of a quilting-frame which embodies my invention.

Figure 3, on a larger scale, is an elevation of a section, at the line Y Y in figs. 1, 4, and 5, of one of my improved quilting-frame couplings applied to the fixed and rolling-up bars at one corner of the frame.

Figure 4 is an elevation of a section of the same at the line X X in figs. 1, 3, and 5, and

Figure 5 is a plan view of the same

Figure 6 is an elevation of the upper part of one of the legs of the frame applied to one of the fixed bars.

Like parts are marked by the same letters in the different figures.

This invention consists in an improved coupling for connecting the fixed and rolling-up bars of a quilting-frame in such manner that when the rolling-up bars are connected to the fixed bars by such couplings, with a quilt on the bars, the pulling back and turning of one of the rolling-up bars to roll up the quilt thereon, will release or loosen the couplings of such rolling-up bar upon the fixed bars, and cause those couplings to slide along on the fixed bars as the rolling up of the quilt progresses, and so that the couplings may be re-fastened upon the fixed bars, by drawing back the rolling-up bar to strain the quilt tight, and then releasing the rolling-up bar with a slight unrolling movement.

My improved quilting-frame coupling consists essentially of a stock, A, formed with a socket, or guides, b, so as to slide on a fixed bar, C, of a quilting-frame without turning thereon; a ratchet, D, journaled in or upon and carried by the stock A, and having a socket, e, to receive and hold without turning upon the rolling-up bar F; and a pawl, or dog, G, pivoted to the stock A, and having one catch, h, fig. 3, for taking into the teeth of the ratchet D, and another one, i, for simultaneously biting into or engaging with the fixed bar C; all constructed and arranged so that when the rolling-up and fixed wooden bars of a quilting-frame shall be connected together by such couplings, with a quilt, J, fastened to and strained tight between the rolling-up bars F F, substantially as shown by the drawings, the catches h and i, of the pawls G, will then engage with the teeth of the ratchets D, and with the fixed soft-wood bars C, as indicated in figs. 2 and 3, so as to thereby keep the stocks A from sliding on the fixed bars, and also prevent the rolling-up bars F from being turned in the stocks A by the tension of the quilt.

And so that by drawing back and turning backward one of the rolling-up bars, as indicated by the arrow k

in figs. 1, 2, and 3, to roll up the quilt on that bar, the ratchets D D, on that bar will then lift, or disengage the catches i from the fixed bars C, somewhat as indicated by dotted lines in fig. 3; and the two stocks, A A, which support that rolling-up bar, will then be slid along on the fixed bars, as the rolling up of the quilt progresses.

And so that by then pulling back on such loosened rolling-up bar, as indicated by the arrow m, to strain the quilt tight, and then turning that bar a little forward, as indicated by the arrow n in fig. 3, the catches h, of the dogs G for that bar, will engage with the teeth l, of the ratchets D, and thereby make the stops i of the dogs engage with the fixed bars, so as to thereby refasten the stocks A A to the fixed bars against the tension of the quilt.

In fig. 2, o is a spring, to pull the catch i down against the bar C. But I generally make the dog G so heavy on the side of its catches as to thereby keep it in place, and make it engage with the ratchet and fixed bars properly.

By having the bars F extend through the sockets in the ratchets D, the frame may be adjusted to quilts of different widths.

I construct my improved coupling of any proper shape and materials, and secure the parts together by any suitable known means.

In fig. 4, p p, are the journals of the ratchet D, fitted to turn freely in the sides g g, of the stock A; and r is a stud, on which the dog G is pivoted to the stock.

In the drawing, the stock A is shown formed of plate-metal, the lower part, s, being a plate bent down at both ends, and punched to receive and form a socket, or guides for the fixed bar, and the sides q q are punched to receive the journals p p, of the ratchet D, and have bottoms, t t, bent at right angles, and fastened by screws, u, to the part s.

In figs. 3 and 4, the lower part of the stock A is shown extended and perforated, so as to receive and be screwed fast to a leg, V.

In figs. 1, 2, and 6, the leg V has a bent metal cap, w, to fit and slide upon the fixed bar of the frame.

What I claim as my invention, and desire to secure by Letters Patent, is—

A quilting-frame coupling, composed essentially of a stock, A, to slide on the fixed bar of the frame, a ratchet, D, journaled in the stock, and having a socket for holding the rolling-up bar, and a dog, G, pivoted to the stock, and having catches, h and i, for engaging with the ratchet and with the fixed bar, all constructed and arranged so as to operate substantially as herein set forth.

In testimony whereof, I hereunto set my hand, this 11th day of January, 1869.

ISAAC W. VALANCE.
